UNITED STATES PATENT OFFICE.

EWALD DEMMER, OF BARMEN, GERMANY, ASSIGNOR OF ONE-HALF TO
RUDOLF DISSELKAMP, OF SAME PLACE.

STOVE FOR LIGNITE CAKES, PEAT, &c.

SPECIFICATION forming part of Letters Patent No. 621,800, dated March 28, 1899.

Application filed January 3, 1898. Serial No. 665,398. (No model.)

To all whom it may concern:

Be it known that I, EWALD DEMMER, a subject of the Emperor of Germany, and a resident of the city of Barmen, in the county of Rhenish Prussia, Germany, have invented certain new and useful Improvements in Stoves for Lignite Cakes, Peat, and the Like Fuel, of which the following is a full, clear, and exact specification, such as will enable others skilled in the art of this manufacture to make and use the same, reference being had to the accompanying drawings, and to the letters of reference marked thereon, which form a part of this specification.

15 The invention has reference to such stoves which permanently are burning and which are fired with fuel of less value—as, for instance, lignite peat and the like. Such fuel may be preferably used in coal-cake form. 20 The stove is thus constructed that the bituminous gases produced from the said fuel cannot enter into the room, but are perfectly burned, and that for feeding the stove with air such air will be taken from above the 25 stove, where it is spoiled. The heating effect of my stove is therefore much greater than of a stove fired with ordinary coals.

The manner in which I carry my invention into effect is shown on the accompanying drawings, in which—

Figure 1 illustrates a vertical section of the improved stove for lignite. Fig. 2 is a similar section at right angle to Fig. 1. Figs. 3 and 4 are horizontal sections along lines I I 35 and II II of Fig. 1.

The same letters of reference denote the same parts in the several figures of the drawings.

The reference-letter *a* denotes the outer 40 casing of the stove, which may have any convenient form. In the present example I have made it circular and is provided with a bottom *b*.

c is a bottom plate which is arranged in the 45 lower part of the casing to provide a chamber *d*. On this plate stands a second cylinder *e*, forming, with the casing *a*, a chamber or flue *g*, which is closed at the top by a suitable plate *f*. Concentrically to the cylinder 50 *e* is arranged in the stove a fuel-chamber *h*, resting upon the plate *c*, with legs *h'*. Be-

tween the cylinder *e* and the fuel-chamber *h* is thus formed a chamber which is closed at its top by a plate *i* and partitioned by a plate *k* in two chambers *g' g*. Both plates *i k* have 55 apertures *l l'*, the lower of which is adapted to receive a blast-pipe *m*. Above the chamber *h*, which is provided with a sliding damper *k'*, is mounted the horizontal exit-pipe *n*, having connection to the flue *g* and extending 60 over the casing *a* in order to be joined to the chimney-tube.

The top part of the stove is preferably made of ball form and carries an air-valve *o* of any known and suitable construction. The bottom of the stove contains, as before described, the chamber *d*, in which is separated a room *p*, serving as an ash-pit and containing a pan *p'*. Over the pit is arranged in the bottom plate *c* the fire-grate *c'*, having a second 70 sliding grate *c*², which is provided with pins *c*³, that project through the slots of the grate *c'* for the purpose of stirring the ash when being moved by its handle *c*⁴. Now the chamber *d* has connection to the flue *g* by slots *q* 75 and also to the chamber *g*² by a slot *q'*, Fig. 4, these slots being cut in the bottom plate *c* and the room *g*² being connected to the ash-pit *p* by a small tube *r*. Two doors *s s'*, the first for filling the shaft *h* with lignite cakes 80 and the other for igniting the fuel and controlling the fire, are hinged to the stove, the working of which is as follows: After filling the stove with fuel, for which purpose the damper *k'* is withdrawn, and igniting the fire 85 the air-valve *o* is opened and air may run into the chamber *h*. The fire-gases evolving on the hearth descend through the back slot *q'* into the chamber *d*, and from there they pass through the slots *q* into the flue *g*, entering 90 at the top part of it the exit-pipe *n*, through which they are issued into the chimney. On its long way the gases are abundantly fed with air, so that a large fire may be kept in the stove. If a small fire is required, the 95 chamber *h* is shut off by the damper *k'*. The feeding-air enters then the hearth through the openings *l l'*, and the blast-pipe *m*, which has a sucking action, furnishes only so much air as for a small burning of the fire is required. The gases are traveling the same way as before. If the air-valve is closed, the fuel 100

is only glowing without being able to extinguish, as the upper part of the stove, serving as an air-reservoir, contains a large stock of air. The glowing ash drops into the ash-pit, 5 and the gases which are here still evolved may escape through the pipe *r* into the room *g*², where they go the prescribed way. In such a manner no products of combustion can enter the room and spoil the air. The latter is, 10 on the contrary, improved, as the air-feeding contrivance is attached to the top portion of the stove and the air is sucked on from the upper layers of the room.

Having thus described my invention, I declare that what I claim, and desire to secure 15 by Letters Patent, is—

A stove having two concentrically-arranged casings as *a*, *e* a central combustion or fuel

chamber as *h* fitted with a movable damper, partition-plates *i*, *k*, with openings *l*, *l'* and 20 a blast-pipe *m*, attached to plate *l'* a horizontal gas-exit pipe as *n*, the chambers and flues *d*, *g*, *g'* *g*² being connected by slots *q*, *q'* respectively, forming communications between said chambers and flues an ash-pit *p* and a pipe *r* 25 connecting the ash-pit with room *g* an air-valve *o* on the top of the stove all as illustrated, described and for the purpose set forth.

In testimony whereof I have hereunto set 30 my hand in the presence of two subscribing witnesses.

EWALD DEMMER.
